UNITED STATES PATENT OFFICE

120,482

DESIGN FOR AN AUTOMOBILE

Howard A. Darrin, Brentwood, Calif.

Application November 27, 1939, Serial No. 38,508

Term of patent 7 years

To all whom it may concern:

Be it known that I, Howard A. Darrin, a citizen of the United States, residing at Brentwood, Los Angeles, in the county of Los Angeles and State of California, have invented a new, original, and ornamental Design for an Automobile, of which the following is a specification, reference being had to the accompanying drawing, forming part thereof.

This application is a continuation in part of the application filed October 7, 1938, and bearing Serial No. D-80,306.

In the drawing:

Fig. 1 is a side elevational view of an automobile, showing my new design, with the top of the automobile and the side window both in lowered position.

Fig. 2 is a side elevational view of the automobile of Fig. 1 with the top, and also the side window in raised position.

Fig. 3 is a top plan view of the automobile, with the top raised as in Fig. 2.

Both sides of the automobile are substantially the same.

The dominant feature of my design resides in the portions thereof shown in solid black lines in the drawing.

I claim:

The ornamental design for an automobile, substantially as shown and described.

HOWARD A. DARRIN.
